UNITED STATES PATENT OFFICE.

MARSHALL B. LLOYD, OF MENOMINEE, MICHIGAN, ASSIGNOR TO HEYWOOD-WAKEFIELD COMPANY, OF BOSTON, MASSACHUSETTS, A CORPORATION OF MASSACHUSETTS.

THROWN-SHUTTLE WEAVING MACHINE.

Application filed January 15, 1926. Serial No. 81,523.

This invention relates to improvements in thrown shuttle weaving machines or looms and it consists of the matters hereinafter described and more particularly pointed out 5 in the appended claims.

The main object of the invention is to provide a weaving machine or loom for reed fabric and the like, which machine embodies a thrown pinch shuttle, adapted to lay a 10 stake in a filler strand or warp member shed, at each throw or movement of the shuttle, whereby weaving at high speed may be attained.

A further object of the invention is to 15 provide a weaving machine for reed and like fabrics, which includes a thrown shuttle carrying a pinching or gripping means at each end thereof and which are so co-ordinated with fixed parts of the machine that 20 at one end of the throw, the trailing, pinching means is automatically actuated to open and release its stake and lay the same in the shed and the advancing pinching means is automatically closed to grasp a stake and 25 to lay the same in the newly formed shed and so on, the pinching means acting in alternation to grasp a stake, lay the same in the shed and then release the same.

A further object of the invention is to 30 provide such a machine, wherein the shed forming mechanism may be readily controlled as by a jacquard to arrange the filler strands or warps in that order in the shed, so that figures may be produced in the finished fabric at the desired intervals.

My invention consists generally in mechanism of the form, arrangement and coaction of the parts thereof whereby the above mentioned objects, together with others that 40 will hereinafter appear, are attainable; and my invention will be more readily understood by reference to the accompanying drawings which illustrate what I consider at the present time, to be the preferred embodiment 45 thereof.

In said drawings:—

Fig. 1 is a perspective view of one side of a weaving machine embodying my invention.

Fig. 2 is a transverse vertical sectional view through the same as taken on the line 50 2—2 of Fig. 1.

Fig. 3 is a longitudinal vertical sectional

view through the shed forming mechanism thereof as taken on the line 3—3 of Fig. 2.

Fig. 4 is a top plan view, on an enlarged 55 scale of the parts shown at the right hand end of Fig. 2.

Fig. 5 is a longitudinal vertical section through the parts shown in Fig. 4, as taken on the line 5—5 thereof.

Fig. 6 is a transverse vertical detail sectional view as taken on the line 6—6 of Fig. 5.

Fig. 7 is a horizontal detail sectional view as taken on the line 7—7 of Fig. 3.

In general, my improved weaving machine is of the thrown shuttle type but it differs materially from the ordinary thrown shuttle loom in that the shuttle carries no weft pirn or bobbin but is a duplex pinch shuttle, that 70 is the shuttle carries a stake or weft pinching or gripping means at each end, said means operating at each pick of the loom to alternately lay in one stake and pick up a new stake or weft and so on.

Referring now in detail to that embodiment of the invention illustrated in the accompanying drawings: 1 and 2 indicate respectively the upright side frame members of the machine or loom, which members are 80 held in the desired spaced relation in any suitable manner. Associated with the side frame member 1 but spaced latterly from the mid portion thereof is a supplemental upright frame member 3 best shown in Fig. 85

1. Extending transversely between and journaled in suitable bearings arranged on the mid portions of said side frame members are top and bottom horizontal shafts 4 and 5 respectively, the former being hereinafter 90 termed the "cam shaft" and the latter being hereinafter termed the "drive shaft" because it is from this shaft that all operating parts are driven.

One end of each of said shafts projects 95 beyond the side frame member 1 and to the end of the drive shaft is fixed a combination gear having a spur gear part 6 and a bevel gear part 7. Journalled in suitable bearings on the supplemental frame member 3 is a 100 longitudinally extending counter shaft 8, on the front end of which is fixed a bevel pinion 9 meshing with the bevel gear 7 and on the rear end of which is fixed a large spur gear

10. Said spur gear meshes with a pinion 11 on the armature shaft of an electric motor 12 all as best shown in Fig. 1. On the projecting end of the cam shaft 4 is fixed a 15 spur gear 13 which meshes with the spur gear part 6 of said combination gear. It is apparent from the foregoing that the drive shaft is rotated at the proper speed in a counter clockwise direction and the cam 20 shaft is rotated in a clockwise direction, as best shown by the arrows in Fig. 1.

Forwardly of the cam shaft is arranged, the reciprocating or swinging beam 14 of the weaving machine. Said beam extends 15 transversely of the machine and is mounted on the top ends of beam arms 15—15 one adjacent each side frame member 1 and 2 respectively. The bottom end of each arm is journaled on studs 16—16, one projecting 20 inwardly from each side frame member. Secured to and rising from the rear side of the beam is a reed 17 including a plurality of closely spaced dents 18 through which the warp like filler strands 19 pass in closely 25 adjacent planes there being a shuttle guide rail or flange 14^a arranged between the beam and the bottom portion of the reed. Forward and rearward reciprocating or swinging movement is imparted to the beam as 30 follows:—On the cam shaft 4 is fixed two cam discs 20—20 each having a cam groove 21 in one face thereof. Said cam groove is disposed eccentrically with reference to the shaft 4 and that part of the groove spaced 35 the greatest distance from said shaft is made concentric therewith as shown at 21^a to provide the "dwell" portion thereof. To the rear of said cam shaft are links 22 one for each cam groove and the top end of each 40 link is pivotally secured to a bracket 23 fixed to the inner surfaces of the rear portions of upright extensions 24 of the side frame members. To the bottom end of each link is operatively connected the rear end of a connecting rod 25, the forward end of which is likewise connected to the beam 14. On 45 each link 22 midway between its ends, are rollers 22^a each operatively engaged in an associated cam groove 21. It is apparent, that through the cams 20, links 22 and rods 25, a reciprocating or swinging movement is 50 imparted to the beam for each rotation of the cam shaft, with the beam in a momentary position of rest while in its rearmost position due to the dwell of the cams 20. When 55 said beam is in this position, it is inclined slightly downwardly and rearwardly from the horizontal as best shown in Fig. 3.

60 Between the beam 14 and the cam shaft 4 is located a shed forming mechanism or harness indicated as a whole by the numeral 26 in Fig. 3. Said harness includes a comber frame comprising top, bottom and intermediate comber boards 27—28 and 29 respec-

tively extending between and supported by the forward portions of the upright extensions 24 of the side frame members 1 and 2. Associated with said comber boards and vertically slidable in suitable bearing openings therein is a plurality of lingoes or heddles 30. In this instance said lingoes or heddles are in the form of relatively stiff though lightweight metal rods or tubes each having a transversely disposed eye or opening 30^a for the passage therethrough of the associated filler strand or warp member 19, the shedding movement of which it controls. The said lingoes or heddles are so disposed in the comber boards that the warp members 80 pass through the harness in side by side relation from suitable feed and tension devices at the rear end of the weaving machine as indicated as a whole by the numeral 31 in Fig. 1. As the construction of the said warp strand feeding and guiding means may be of any suitable kind and therefore forms no particular part of the present invention, it is not thought necessary to go into a detailed description thereof. To the top end of each 90 heddle is connected a neck cord 32 the entire group of which is operatively associated with a jacquard control mechanism of the desired kind but not herein illustrated. It is apparent from the foregoing that the 95 filler strands or warp members may be manipulated in the desired manner to form the succeeding sheds into which the weft stakes are inserted and laid and then beaten home in the finished fabric.

Projecting laterally from each side frame member 1 and 2, in the plane of the beam 14 when the same is in its rearward and momentary position of rest, is a fixed beam extension or shuttle station 35—35 as best shown in Fig. 2 said extension including an upright flange 35^a at the rear side thereof which in effect form continuations of the rail 14^a of the beam. The inner end of each beam extension, which projects a short distance inwardly of the plane of the associated side frame member, is supported therefrom by a bracket 36 while the outer end of each beam extension is supported upon the top end of a tubular post or leg 37 rising from the floor or base upon which the machine as a whole stands. It is upon said extension, that the shuttle 38 employed in the loom comes to its momentary position of rest at each pick of the loom and hence the term "station."

The shuttle 38 while of the pinch shuttle type is indeed different from pinch shuttles hereto employed in reed fabric weaving machines wherein the shuttle was mounted on the end of a long arm reciprocable in a raceway at one side of the machine and which inserts a weft or stake for each entire cycle or complete reciprocation, the said shuttle pinching upon a stake at one end of its

movement and drawing the same through the shed and depositing it in the shed when the shuttle arm reaches the other end of its movement.

5 The shuttle employed in the machine herein described is of the thrown shuttle kind and is duplex in its nature, in that it carries a stake pinching or gripping means 39 at each end so that at the end of each throw thereof, one stake 19^a is released by and laid in the shed by the pinching means at the trailing end of the shuttle while another stake is grasped by the advancing end of the shuttle to be drawn through and deposited in the shed. As the shuttle is thrown in the opposite direction, the first mentioned (or trailing) end of the shuttle becomes the advancing end, and the second mentioned (or advancing) end of the shuttle becomes 15 the trailing end thereof, the terms "trailing" and "advancing" being relative to the direction of movement or throw of the shuttle. Said shuttle as best shown in Fig. 5 includes upright trigger members 39^a between 20 its ends, each associated with and adapted to control the opening and closing movements of said pinching means or fingers as will later appear. As the construction of the shuttle forms the subject matter of my co- 25 pending application filed Jan. 15, 1926, under Serial Number 81,524 and is fully set forth therein, it is not thought necessary to again repeat the same here as the above mentioned general description should suffice.

30 35 As the means for throwing the shuttle from one beam extension or station to the other is duplicated at each side the machine and as the shuttle throwing means associated with each station is the same, a detail description of one only will be given.

To the rear of each beam extension is a rail or guide 40 in the form of a cylindrical rod fixed at its ends in brackets 41 carried by said beam extension. Slidable on said 40 rod is one end of a picker block 42, the other end of which extends through a slot 35^b in the extension flange 35^a and is formed to provide a shuttle end receiving head or socket 43. In the shuttle block between the 45 rail 40 and flange 35^a on the beam extension is provided a vertically disposed and elongated slot 44 through which the top end of a picker stick or arm 45 projects. Said stick is pivoted near its bottom end on a laterally 50 extending stud 46 on the associated side frame member so as to be capable of a swinging movement in a direction parallel with the beam extension. Said stick includes a short extension 47 on its bottom end which 55 is connected by a contractile spring 48 with the side frame member, said spring normally acting to return the picker stick to its outer position as shown in full lines at the right hand side of Fig. 2.

60 65 The shuttle throwing movement of the

stick is imparted thereto as follows: Extending inwardly from each side frame member, are pairs of front and rear brackets 50—50 and in each pair of brackets is journalled a longitudinally extending rock 70 shaft 51 of rectangular cross section. Fixed to each shaft between the brackets of each pair of brackets and in substantially the vertical plane of the drive shaft 5 is an arm including a longitudinally disposed cam 75 like flange 52 which is curved upwardly towards its rear end. On the front end of each shaft 51, which projects a suitable distance beyond the associated front bracket 50 is an upwardly extending crank arm 53. 80 To the top end of each crank arm is operatively connected, the inner end of a link 54 the outer end of which carries a stirrup 55 through which the associated picker stick extends, there being a shock absorbing 85 pad 55^a interposed between each stirrup and its picker stick. Rigidly secured to the drive shaft 5 is substantially the plane of the rockshafts 51 are arms 56, 56, the one being set on the shaft to extend diametrically 90 opposite the other as best shown in Fig. 2. The outer end of each arm carries a roller 57 which in the rotation of the arm with said drive shaft, engages the cam flange 52 and thus rocks the shafts 51—51 inwardly 95 in alternation. After the roller leaves the cam flange, the springs 48 before mentioned, return all parts to their normal position.

As the picker sticks act to throw the pinch shuttle through the shed from one beam extension or station to the other at an extremely high speed, means are provided on each station to brake or slow down the movement thereof as it approaches the ends of its throw, otherwise great damage might 100 result, not only to the shuttle but also to the picker block and correlated parts. To thus brake or slow down the shuttle movement at each end of its throw I provide the following mechanism. On the front side at 105 the outer end of each beam extension, I provide a bracket like member 60 (see Figs. 2 and 4) to the inner end of which is pivoted on a vertical axis as at 61 a relatively, long, vertically edgewise disposed brake shoe 110 or plate 62 which is yieldingly held against swinging movement away from the beam extension by a leaf spring 63. Inward swinging movement of said brake shoe is limited 115 by a clip like plate 64 carried by the inner end of the brake shoe for engagement with the beam extension. It will be noticed from Fig. 4, that the inner end of said brake shoe, which is curved as shown is normally spaced closer to the associated beam flange 35^a than 120 is the bracket 60 to which it is connected. This restricts the entrance of the shuttle, into the station so that as the shuttle approaches the same at the end of its throw, it engages with the brake shoe which yields 125 130

outwardly slowing down the shuttle, so that its advancing pointed end enters the socket or head of the picker block. The brake shoe, yielding as it does, will also check the rebound of the shuttle so that it will be in the proper position to be thrown in the opposite direction. Should for some unforeseen reason, the shuttle stop in a position bridging the gap or space between the beam and 10 one of the beam extensions in the movement of the beam, the shuttle will act to force the brake shoe outwardly so that no damage will result to the shuttle.

On the flange 35^a of each extension are 15 mounted inner and outer tripper blocks 65 and 66 respectively adapted to be engaged by and to actuate the triggers 39^a on the shuttle to automatically open and close the pinching means at each end thereof. Said blocks have screw and slot connections with 20 said flange 35^a so as to be capable of being adjusted to the proper position thereon with respect to the triggers of the shuttle, the operating portions of said tripper blocks being 25 relatively offset as best shown in Fig. 4, the triggers of the shuttle being likewise offset as is apparent so that one of said tripper blocks can in no way interfere with the shuttle trigger adapted to be actuated by the other tripper block.

In the operation of the machine, the filler strands or warp members are manipulated by the harness, in turn controlled by the jac- 35 quard neck cords so that the desired position of the various strands or warp mem- bers is attained in each shed. Thus the strands are so manipulated that plain flat fabric is produced wherein the individual strands are arranged "over and under" the 40 stakes in alternation and in portions of the fabric, a contrast of appearance is produced therein by passing a group of adjacent filler strands or warp members over the same side of one stake and under another to form the 45 desired figure. The sheds of course are formed in timed relation with the movement of the beam and when the beam is at its rear- 50 ward and momentary position of rest as shown in Fig. 3, one of the picker arms acts to throw the shuttle in one direction, the shuttle having previously grasped or 55 pinched by the means now on its trailing end, a stake 19^a. As the shuttle reaches its other station, the tripper blocks 65 and 66 are engaged by the triggers of the shuttle which releases the stake within the shed and picks up another one for its movement in the other direction. As soon as a stake is 60 deposited in a shed at which time the shuttle has cleared the beam end, the beam moves forwardly and beats home the stake into its position in the fabric and then immediately returns to its rearward position, a new shed being formed in the meantime. The fabric 65 is wound as it is formed upon a take up roll

67 at the forward end of the machine which is rotated step by step for this purpose. As the parts for imparting such movement to the take up roll, form no particular part of the present invention, it is not thought necessary to either show or describe the same in more detail here. 70

The weaving machine is positive and efficient in operation and is indeed fast in the production of fabric. As it lays a stake in 75 place at each throw, it is twice as fast as a pinch shuttle loom for the same purpose, which lays a stake for each complete back and forth movement of the shuttle.

While in describing my invention I have 80 referred to many details of construction as well as form and arrangement of the parts thereof, the same is to be taken as by way of illustration only and not by way of limitation except as may be pointed out in the 85 appended claims.

I claim as my invention:

1. A loom embodying therein, a recipro- 90 cible beam, means providing fixed exten- sions therefor when said beam is in one posi- 95 tion, means for throwing a shuttle having trigger actuated grippers from one extension across the beam to the other extension when said beam is in said position, and means in- cluding longitudinally spaced tripper blocks on each extension arranged to overhang the shuttle when on said extension and adapted to actuate the triggers thereof.

2. A loom embodying therein, a recipro- 100 cible beam, means providing fixed extensions therefor when said beam is in one position, means for throwing a shuttle having trigger actuated grippers from one extension across the beam to the other extension when said beam is in said position, and means in- 105 cluding longitudinally spaced tripper blocks on each extension arranged to overhang the shuttle when on said extension and offset into different planes transversely of the ex- 110 tension and adapted to actuate the triggers thereof.

3. A loom embodying therein, a recipro- 115 cible beam, means providing fixed extensions therefor when said beam is in one position, each extension including an upright back flange, means for throwing a shuttle having trigger actuated grippers from one extension across the beam to the other extension when said beam is in said position, and a pair of 120 longitudinally spaced tripper blocks sup- ported on said back flange and including parts arranged in different planes trans- versely of the extension to overhang the shuttle while on said extension and adapted to actuate the triggers thereof. 125

4. A loom embodying therein, a recipro- 130 cible beam, means providing fixed exten- sions therefor when said beam is in one po- sition, each extension including an upright back flange, means for throwing a shuttle 135

having trigger actuated grippers from one extension across the beam to the other extension when said beam is in said position, and a pair of longitudinally spaced tripper blocks having a longitudinal screw and slot adjustment on the back flange and including parts arranged in different planes trans-

versely of the extension to overhang the shuttle while on said extension and adapted to actuate the triggers thereof.

10

In testimony whereof, I have hereunto set my hand, this 17th day of December, 1925.

MARSHALL B. LLOYD.
